CLAIM

The ornamental design for a display screen, or portion thereof, with a graphical user interface for a baccarat game, as shown and described.

DESCRIPTION

FIG. 1 is a front view of the display screen, or portion thereof, with a graphical user interface for a baccarat game showing our new design according to a first embodiment; FIG. 2 is a front view of the display screen, or portion thereof, with a graphical user interface for a baccarat game showing our new design according to a second embodiment of FIG. 1 and including example game-play information illustrated in broken lines; and,

FIG. 3 is a front view of the display screen, or portion thereof, with a graphical user interface for a baccarat game showing our new design according to a third embodiment. The heavier broken lines show the display screen, or portion thereof. The other broken lines show portions of the graphical user interface. The broken lines, heavy and otherwise, are provided for the purpose of illustrating portions of the article and form no part of the claimed design.
